CAN STRAIGHTENER

John L. Rickhoff and Edward A. Rickhoff,
Corona, Calif.

Application October 1, 1948, Serial No. 52,208

12 Claims. (Cl. 153—32)

1

The application relates to machines which are expressly devoted to ironing out dents in cans. It has more particular reference to a power-operated device which is capable of rolling out indentations and dents which accumulate in cans and particularly narrow-neck cans such as large milk cans.

In the handling of milk in large quantities where farmers having dairy herds have occasion to ship milk to some central collecting point there is considerable use for five, ten and fifteen gallon cans in which the milk is shipped. Inasmuch as under many circumstances milk is produced on farms where the milk must be handled by individuals without the aid of machinery, can sizes of the capacity indicated are in most frequent use. When the cans have been filled with milk, they are loaded on a pick-up truck or other vehicle, transported over rough roads and eventually deposited at some central collecting point. After the milk has been emptied from the cans, the cans are returned by a similar route to the farmer.

In the ordinary course of handling and particularly during the return of empty cans, the cans are jostled about in transit, dropped upon hard surfaces, dumped over in many instances, and treated in general in such a way that over a period of time a great number of dents accumulate in the cans which impair their utility to a considerable extent. Cans and containers of this particular character are relatively high priced so that it becomes advantageous to straighten the cans and continue their use for as long as possible rather than to discard them for new cans. In order, however, to straighten the cans economically, the operation must be a rapid one and capable of being performed as much as possible by machine.

It is, therefore, among the objects of the invention to provide a new and improved can straightening machine which is rapid in its operation for setting up the can, for straightening out the dents and for release of the can once the straightening operation is completed.

Another object of the invention is to provide a new and improved can straightening machine which is adapted to be effectively operated without consumption of more than a moderate amount of power.

Still another object of the invention is to provide a new and improved can straightening machine which is adapted to reach all portions of both straight and curved walls of cans of the character of milk cans of large capacity, and wherein the portion of the device adapted to the

ironing out of the dents and depressions can be worked gradually over the surface so that not all of the dents need to be ironed out at the same time thereby conserving an appreciable amount of power.

Still further among the objects of the invention is to provide a can straightener wherein a straightening head is adapted to be collapsed and lowered into a can and which, upon reaching the bottom of the can, automatically expands into engagement with the can walls whereupon manual means becomes operative to modify the degree of expansion.

Also included among the objects is the provision of means for modifying the degree of expansion to accommodate cans of different diameters and heights.

With these and other objects in view, the invention consists in the construction, arrangement and combination of the various parts of the device whereby the objects contemplated are attained, as hereinafter more fully set forth, pointed out in the claims and illustrated in the accompanying drawings, in which:

Figure 1 is a side elevational view of the machine partly broken away to reveal certain structure otherwise concealed.

Figure 2 is a fragmentary cross-sectional view taken on the line 2—2 of Figure 1.

Figure 3 is a side elevational view taken along the line 3—3 of Figure 1 and partly broken away to show interior structure.

Figure 4 is a fragmentary vertical sectional view taken on the line 4—4 of Figure 1.

Figure 5 is a plan view taken on the line 5—5 of Figure 4 with the can removed.

Figure 6 is a vertical sectional view showing the straightening head in collapsed condition in a can.

Figure 7 is a view similar to Figure 6 showing the straightening head in expanded position.

Figure 8 is a vertical sectional view taken on the line 8—8 of Figure 7.

Figure 9 is a cross-sectional view taken on the line 9—9 of Figure 8.

Figure 10 is an elevational view partly in section illustrating the construction of one side of the straightening head.

Figure 11 is a vertical sectional view similar to Figure 7 showing the device adapted to the straightening of a can of slightly different size.

Figure 12 is a cross-sectional view on the line 12—12 of Figure 11 with the straightening head removed.

As illustrated in the figures, the embodiment chosen to illustrate the invention is adapted to

the reception and straightening of a can ordinarily identified as a milk can. In use clamps on the machine are released and the can is set in position adjacent the clamps. By use of hydraulic cylinders the clamps are closed to hold the can in stationary position. Once in position other mechanical means are set in motion so that a straightening head or device including straightening rollers can be lowered through the neck of the can to the bottom of the can and there expanded so that the rollers roll around the surface of the walls whereby to press the dents outwardly. The clamp which holds the can in place forms in part a backing or resistance against which the rollers are adapted to press. The straightening head is adapted to progress from the bottom of the can upwardly toward the top. Upon completion of the straightening operation the straightening head can be collapsed and power means again placed in operation to lift the straightening head from the can. Either during or following the above described straightening apparatus a special device, illustrated in Figure 4, can be placed in operation for ironing out or straightening the rim of the bottom of the can. The last defined device can also be used as a means for additionally locating the can in place in the machine. Once the straightening operation is completed the clamps can be released and the can lifted from its position in the machine.

The framework of the machine consists of a bed frame or base adapted to be supported upon some solid surface such as a concrete platform in which there can be sunk a well for the support of a vertical column and within which may be positioned a hydraulic ram. The column extends a substantial distance above the bed frame in order that it may be capable of suspending the straightening head above a can of the largest size ordinarily encountered and be adapted to lower the head into the can and lift it clear.

As shown in detail in Figures 1 and 3, a bed frame 10 is here shown as comprising front end posts 11 and rear end posts 12. Beams 13 comprising angle irons connect the front and rear end posts, and cross-beams 14 extend between the posts on opposite sides. A vertical column 15 is here illustrated as being constructed of angle irons in spaced face to face relationship, the bottom portion of the column being secured in a base 16. At the top of the column is a cross-beam 17 and a brace 18 extends from the cross-bar downwardly to an extension 19 extending laterally from the bed frame adjacent the tops of the posts 11. The column is designed to carry a head stock 20 containing a motor and machinery for the operation of a can straightening head indicated generally by the reference character 21.

When a can is to be placed upon the machine a pair of clamps 22 and 23 are opened by operation of a horizontal hydraulic ram indicated generally by the reference character 24. The ram is adapted by reciprocation of a piston 25 to shift the clamp 23 back and forth between a clamped and an unclamped position.

As illustrated in Figure 1, the hydraulic ram 24 is shown in a position connected to longitudinal beams or rails 26 and 27, the rails being attached to the tops of the posts 11 and 12. Within the rails, here shown in the form of angle irons, are mounted slides 28 and 29 which are adapted to shift lengthwise with respect to the rails. Connecting the slides is a cross-head 30, and

the cross-head is designed to be secured to the clamp 23. The piston 25 is also secured to the center of the cross-head as illustrated in Figure 2. The other clamp 22 is stationarily mounted in position with relation to the rear ends of the rails 26 and 27.

In closed position wherein a can 31 is to be clamped in place the clamps 22 and 23, once they have been pressed together by operation of the hydraulic ram 24, are locked in place by lugs 32 on horizontal flanges 33 which overlie corresponding portions of horizontal flanges 34. Vertical flanges 35 and 36 provide a seating surface between the edges of the clamps.

Power for operating the hydraulic ram is derived from an electric motor 40 which is adapted through a suitable mechanism to operate the hydraulic pump 41 by means of which hydraulic fluid is conveyed through a hydraulic line 43 to the cylinder of the ram 24. A return line 45, a part of which is illustrated in Figure 1, conducts hydraulic fluid back to the pump. The elements of the hydraulic system are substantially conventional and are not described in detail herein.

Once in position the can is ready for the straightening operation. This is achieved first by manipulation of the head stock 20 by means of a vertically disposed hydraulic ram 46. Upon the ram 46 is a piston 47 attached to the head stock and by reason of the long throw of the ram 46 is adapted to lower and raise the head stock 20 over a considerable distance. As has been previously noted, movement of the head stock shifts the position of the straightening head 21.

Although not forming a part of the novel subject matter, attention is directed to utilization of a master hydraulic control valve 50 illustrated to the left of Figure 1 and mounted upon a rear portion 51 of the bed frame, by manipulation of a control handle 52, hydraulic fluid from the pump 42 may be utilized to operate the hydraulic ram 24, and hydraulic fluid from a pump 53 may be utilized to operate the hydraulic ram 46, in each instance through forward and reverse operation.

In normal position the straightening head 21 hangs by gravity in collapsed condition. The collapsed condition is best illustrated in Figures 1 and 6. In collapsed condition the head is normally small enough to freely enter a relatively narrow neck 55 of the can 31. The head is supported in the main by an external tubular shaft 56 and an internal shaft, usually solid, presented by the reference character 57. A key way 58 is provided in the shaft 57 so that it may be keyed non-rotatably to the shaft 56.

As shown, the shaft 56 is suspended from the head stock 21 but is rotatably mounted thereon. There is provided a beveled gear 59 on the external shaft meshing with a beveled gear 60 on a shaft 61 which in turn has a gear box 62 attached at the rear end. The pulley through a system of belts and intermediate pulleys 63 is adapted to be driven by an electric motor 64 mounted upon a platform 65 carried by the head stock 20. Operation of the electric motor causes rotation of the shaft 56 which in turn induces rotation in the straightening head 21.

As shown, the shaft 57 is adapted to slide endwise within the shaft 56. This operation is essential in order to effect expansion and collapse of the straightening head. To accomplish this endwise movement there is attached a block 66 at the upper end of the shaft 57, and the block is

provided with a rack 67. Meshing with the rack is a pinion 68 which in turn is driven by a chain 69 connected to a pinion 70 keyed to a shaft 71 upon which is a wheel 72 adapted to be manipulated by a handle 73. By rotation of the wheel 72 the rack 66 and attached shaft 57 may be raised and lowered with respect to the position of the shaft 56 regardless of the location of the head stock 20. In the present example the head stock 20 includes inside shoes 75 adapted to slide vertically within the sections of the column 15 upon which the head stock and all the attached mechanism is carried.

As best illustrated in Figures 6 and 7, the straightening head 21 includes parts which permit alternate expansion and retraction. As there illustrated, the head consists of a pair of upper parallel arms 80 on one side and a corresponding pair of parallel arms 81 on the opposite side. These parallel arms are pivotally secured by a pivot pin 82 to a bushing 83. The bushing in turn with the aid of an auxiliary bushing 84 is attached non-rotatably to the tubular shaft 56 by use in part of a bolt 85. A key 83' serves to hold the bushing non-rotatably relative to the shaft 57.

Below the parallel arms 80 and 81 are two lower sets of parallel arms 86 and 87. The lower portions of the arms 86 and 87 are pivotally secured by means of pivot pins 88 to a bushing 89 which is keyed by use of a key 89' with relation to the shaft 57 but which at the same time is adapted to slide with relation to the same shaft 57. The parallel arms 86 in turn are pivotally secured by cross-heads 90 and appropriate bolts 91 to the parallel arms 80. Where, as indicated, a clearance is helpful in promoting a more complete collapse of the head, the cross-head may be recessed as shown. By similar means the parallel arms 87 are secured to the parallel arms 81.

A third set of parallel arms 92 on one side and 93 on the other side are secured by pivot pins 94 to a bushing 95 keyed to the bottom of the shaft 57 by use of a key 95'. A shoe 96 may be fixed to the shaft 57 at the bottom of the bushing 95.

On one side the parallel arms 92 are pivotally connected by means of a cross-head 97 to a bolt or shaft 98 which in turn at its other end is secured to a cross-head 99 recessed as shown. The cross-head 99 is pivotally attached to the upper ends of the arms 86. In a similar manner the parallel arms 93 are pivotally secured to a corresponding cross-head 97 on the other side and hence through an appropriate similar shaft 98 to another corresponding cross-head 99. The shafts 98 form the core of vertical, substantially cylindrical composite rollers 100.

On the shafts 98 are provided individual cylindrical roller elements 101, 101' and 101'' of the same diameter which are separated by a roller 103 of different diameter from individual rollers 104, 105, 106, 107 and 108. The individual roller elements, as illustrated in the present form of the invention, include bearings 109 to improve their ease of operation. The roller elements are designed to rotate individually about the shafts so that if need be they may rotate at different speeds. The shafts 98 form portions of the linkage for the lower part of the straightening head, in company with the sets of parallel arms 92, 93, 86 and 87. The lengths of the parallel arms and the shafts between pivot points are made such that there is provided a parallelogram structure whereby the particular alignment of the axes of the shafts 98 is maintained.

In the upper portion of the straightening head 76

are provided another set of composite rollers 110, one on each side. These rollers are identical and comprise shafts 111 mounted at one end in the cross-head 90 and at the other end in a cross-head 112 spanning the distance between the upper ends, respectively, of the parallel arms 80 and 81. Upon the shafts 111 are individual roller elements 113, 114, 115, 116, 117 and 118 arranged side by side and each adapted to be mounted upon a suitable bearing 119. These roller elements are provided with curved contours wherein the curve of each successive element is in alignment with the curve on the adjacent side of the element next in position. By this arrangement the entire composite roller 110 presents a longitudinally curved surface.

Still another element 120 of similar shape is located on the shaft 111 on the side of the cross-head 90 opposite from the roller element 118. It should be noted that the curve of the exterior of the element 120 is such that it is tangent at the outermost portion of the circumference to the outer surface of the roller element 108. The importance of this will appear as an explanation of the operation of the head develops.

For straightening the sides and curved top of the can 31 the can is first mounted and clamped in the machine by means of the clamps 22 and 23 as previously described. For this operation the hydraulic ram 24 is utilized. During the clamping of the can in place the head stock 20 is at its uppermost position, in which position the straightening head 21 hangs clear of the top of the can. In this position, also, the head is collapsed, a condition which it assumes normally as a result of the influence of gravity upon the rollers.

Next, by operation of the hydraulic ram 46 the entire head stock 20 is lowered whereby the straightening head 21 enters the can through the neck 55. The lowering of the head stock continues until the shoe 96 strikes the bottom of the can. During all of this time the head remains collapsed. At this point by continuing lowering the head stock 20 the tubular shaft 56 only is lowered, the shaft 57 remaining stationary by pressure of the bottom against the shoe 96. Because of movement of the shaft 56 relative to the shaft 57 the sets of parallel arms are forced outwardly carrying with them the rollers 100 comprising the roller elements on the shafts 98 and also the composite rollers 110. Initially, only the rollers on the shafts 98 will be in contact with the cylindrical lower wall 125 of the can. The composite rollers 110 will be expanded, but they will be below the curved top of the can herein designated by the reference character 126.

Once the rollers on the shafts 98 come into contact with the cylindrical lower wall of the can, the straightening head can be rotated and by rotation roll the circumferences of the rollers 101, 101', 101'', 104, 105, etc., against any dents which might be present in the can wall. Rotation is usually deferred until the straightening head is lodged within the can so that there will be no centrifugal effect tending to expand the straightening head until it is in position in the can. Rotation is accomplished by operation of the electric motor 64 which causes rotation of the tubular shaft 56 through the shaft 61 and beveled gears 60 and 59. Rotation can be started immediately by the closing of an electric switch 127' mounted on switchboard 127.

While the straightening head is being rotated, the head is gradually raised by manipulation of

the hydraulic ram 46. During the raising operation the extent of expansion of the rollers in the straightening head can be controlled by operation of the wheel 72 by use of the handle 73. In this manner should bumps or dents of exceptional depth be encountered the dents may be ironed out gradually by successive rotations of the straightening head rather than making it necessary by the use of excessive pressure to iron out the dents in a single rotation. For the same reason the roller 103 is made smaller in diameter so that the upper rollers 104, 105, etc., may operate first upon dents at a given level followed by operation of rollers 101, 101' and 101''. The roller 103, being of lesser diameter, will not roll against dents of ordinary depth. Moreover, by manipulation of the wheel 72 the straightening head may be completely collapsed at any time even though the head is rotating at a considerable speed.

As the straightening head continues to be lifted it finally attains the position illustrated in Figure 7. In this position the composite rollers 110 are pressed into contact with the curved wall 126, and at this point any dents in the curved wall are ironed out. By reason of the size and contour of the roller 120, located as it is at the junction of the upper curved wall with the lower cylindrical wall of the can at the uppermost position of the straightening head, all parts of the can wall will be subjected to a straightening operation. The roller 120 in its passage along the topmost part of the cylindrical wall will iron out dents in that portion, and in its uppermost position it will be capable of ironing out downwardly projecting dents at the junction of the curved upper wall with the lower cylindrical wall. Moreover, by reason of the fact that each separate roller rotates independently of the others, the rollers may rotate on their respective shafts at different speeds as different dents are encountered without it being necessary to skid any appreciable surface portion of the rollers over the can surface.

To limit the extent of expansion there is provided a sleeve or collar 129 fixed upon the bushing 83 and another sleeve or collar 132 on the bushing 89. Both sleeves or collars have flanges which abut to limit expansion of the straightening head at its outermost limit.

When the dents in the upper curved portion of the can are finally ironed out, rotation of the straightening head can be stopped by arresting motion of the electric motor 64 at which point the straightening head will collapse, which collapse may be aided by operation of the wheel 72. The straightening head can then be lifted to withdrawn position by continued lifting of the head stock 20.

Under such circumstances, it is desirable to restrict the expansive movement of the straightening head. This may be accomplished by the insertion of shims 130 between the bushings 89 and 95. A suitable number of shims of appropriate thickness can be gaged so as to limit the amount of expansion to one which will properly accommodate the diameter of the can. Still another shim or block 131 may be used between the sleeve or collar 129 and the sleeve or collar 132 which normally rides above the bushing 89.

Because the exterior diameter of an off-size can may be smaller, shims or liners 121 and 121' may be affixed, respectively, to clamps 22 and 23. Ears 122 on the liners extend through appropriate apertures in the clamps and are

locked in position by hooks 123 on hand operated latches 124 extending through the upper flanges 33 and 34.

To further improve the over-all operation of the machine there is provided a means for straightening the bottom rim or flange of the can herein designated by the reference numeral 135. The rim or flange adjoins the rounded bottom 136 of the can. As more clearly illustrated in Figures 4 and 5, there is provided on the bed frame a mounting herein illustrated in the form of a flat plate 137 having wedge-like supports 138 at the outer edge and a large beveled gear 139 on the lower side. The gear is attached to the plate 137 so that the parts form a single assembly, the beveled gear being extended in the form of a shaft 140 of large diameter meeting a bearing 141. The bearing is secured upon a fixed plate 128 carried by the beams 13.

Mounted upon the annular wedge-like flange 138 are slides 142 oppositely disposed and pitched downwardly toward the center. The slides in each case are confined by plates 143 and 144 at the ends and plates 145 and 146 at the sides. The inner ends of the slides are joined by links 147, and the links in turn are pivotally secured by a pin 148 to a plunger 149. An opening 150 in the plate 137 permits mounting of the links, the plunger and the inner ends of the slides. A thrust bearing 151 supports the lower end of the plunger 149, the bearing being illustrated as mounted upon a lever 152 which forms an extension of a treadle 153. The lever 152 is pivoted on a bracket 154, and a spring 155 normally urges the lever 152 in a direction depressing the plunger 149 thereby drawing the slides 142 inwardly to what may be termed "open position." On the lever 152 is a vertical rod 156 bearing a detent 157 at the top designed to fit in a slot 158 on the plate 137. Action of the spring 155 normally moves the detent to a locked position. A slotted tubular guide 159 assists in holding the detent in proper position.

One set of frusto-conical rollers 160 are mounted rotatably on the outer ends of the slides 142. These accommodate a can of the diameter illustrated in Figure 4. A second set 161 of similar rollers accommodate cans of smaller diameter. The sides of the rollers at the point of contact with the inside wall of the flange or rim 135 is vertical.

After a can has been placed upon the mounting with the rim or flange surrounding the rollers 160, the treadle 153 is depressed. This in turn elevates the plunger 149 spreading the links 147 which extends the slides 142 outwardly. This has the effect of pressing the rollers 160 against the inside walls of the flange 135.

At the same time and by the same motion of the lever 152 the rod 156 is depressed releasing the detent 157 from the slot 158. Also at the same time another rod 163 is elevated and through a lever 164 operates a fluid valve 165 which in turn sets a fluid motor 166 in operation.

Through a system of pulleys 167, 168, 169 and 170 a shaft 171 is rotated upon which is a beveled gear 172 meshing with the beveled gear 139. This causes rotation of the plate 137 which in turn effects rotation of the slides 142 and rollers 160 about the axis of the plunger 149. During this rotation each of the rollers 160 rotates upon its own axis and proceeds in ironing out dents, depressions and indentations in the flange 135. One or more rotations are usually sufficient. Upon completion of this operation the treadle

153 is released. While the treadle 153 is released the spring 155 tends to return the lever 152 to initial position and does retract the rollers, but the detent keeps the fluid motor running, and when detent arrives at the recess 158 of the plate 137 it will slide into the recess and the further lift of the lever 152 and rod 163 causes the fluid valve 165 to shut off the fluid motor in the original position namely at the parting line of the clamps. During all of this operation the clamps 22 and 23 remain tight holding the can non-rotatably in position in the machine.

It will be apparent from the mechanisms described that the straightening head may be operated in the can either before or after operation of the straightening rollers upon the flange 135. The rollers may also assist in locating the can upon the mounting prior to forcing the clamps into their position gripping the can. Both straightening operations take place while the can remains in one position on the machine. Both straightening operations may be carefully controlled, and the manipulation of the straightening head is subject at all times to careful manual adjustment by which means the operation may be accommodated to the condition of the can whether it be badly dented with many deep indentations or only lightly dented.

The speed of straightening the can will be influenced by the condition of the can itself and may be speeded up by the operator just as fast as is necessary in order to quickly and effectively complete the job. At the completion of the straightening operation the straightening elements are in a position ready for quick release and withdrawal from contact with the can so that the can may be immediately removed and the machine is at the same time immediately ready for the reception of the next can.

On occasions where the machine is to be used for cans of different stock sizes the bolt 85 may be withdrawn permitting the entire straightening head to be removed from the shafts 56 and 57 making way for a straightening head of similar construction but of smaller dimension. The same clamps 22 and 23 may be used with suitable shims or new clamps of smaller diameter replaced in the machine if a long run is to be made on cans of smaller sizes.

The machine is direct in its operation, makes economical use of both electrical and hydraulic power and is at the same time sufficiently subject to manipulation by a single operator so that the operations can be adjusted to the condition of the work and the operation performed at all times readily, quickly and effectively.

Although the invention has been herein shown and described in what is conceived to be the most practical and preferred embodiment, it is recognized that departures may be made therefrom within the scope of the invention, which is not to be limited to the details disclosed herein but is to be accorded the full scope of the claims so as to embrace any and all equivalent structures.

The invention having been herein described, what we claim as new and desire to secure by Letters Patent is:

1. A straightening machine for open top cans having a rounded wall comprising a bed frame having thereon a clamp adapted to secure the can on the frame, an expansible straightening member adapted to be inserted inside the can having a collapsed condition smaller than the open top of the can, said member comprising a roller means having a position of potential con-

tact with the rounded wall when the straightening member is expanded, a vertically movable head stock supporting said straightening member above the clamp, and vertically disposed operators supporting the straightening member on the head stock having separate relatively movable points of attachment to the straightening member and having vertical movement relative to each other, one of said operators having a fixed vertical engagement with the head stock and the other being vertically movable with respect thereto, said head stock being adapted to lower the straightening member by means of said operators to an expanded condition and to lift the straightening member to a removed collapsed condition, and means adapted to effect relative rotation between the can and the straightening member.

2. A straightening machine for open top cans having rounded lower and upper walls comprising a bed frame having thereon a clamp adapted to secure the can on the frame, an expansible straightening member adapted to be inserted inside the can having a collapsed condition smaller than the open top of the can, said straightening member comprising a roller means having a position of potential contact with the lower wall when the straightening member is expanded, a second roller means having an obliquely disposed expanded position adapted to engage the upper wall, a vertically movable head stock supporting said straightening member above the clamp, and vertically disposed operators supporting the straightening member on the head stock having separate relatively movable points of attachment to the straightening member and having vertical movement relative to each other, one of said operators having a fixed vertical engagement with the head stock and the other being vertically movable with respect thereto, said head stock being adapted to lower the straightening member by means of said operators to an expanded condition and to lift the straightening member to a removed collapsed condition, and means adapted to effect relative rotation between the can and the straightening member.

3. A straightening machine for narrow necked cans having a cylindrical lower wall and a rounded top wall comprising a bed frame having thereon a mounting adapted to receive the bottom of the can, a horizontally moving clamp adapted to enclose the cylindrical lower wall throughout the perimeter thereof and power means for holding said clamp in place, an expansible straightening head adapted for insertion inside the can having a collapsed condition smaller than the neck of the can comprising roller means having a vertical position of potential contact with the cylindrical lower wall when the straightening head is expanded, a second roller means having a longitudinally curved perimeter and an obliquely disposed expanded position adapted when lifted to engage the rounded top wall, power means including a head stock supporting said straightening head above the mounting vertically disposed operators supporting the straightening head on the head stock having separate relatively movable points of attachment to the straightening head and having vertical movement relative to each other, one of said operators having a fixed vertical engagement with the head stock and the other being vertically movable with respect thereto, said head stock being adapted to lower the

straightening head by means of said operators to an expanded condition and to lift the straightening head to a removed collapsed condition, auxiliary manually operative means associated with the straightening head adapted to control the degree of expansion, and means adapted to cause rotation of the head relative to the can.

4. A straightening machine for open top cans comprising a base, a clamping support for the can and a head stock on the base, a straightening member on the head stock mounted above the clamping support, means for raising and lowering said head stock and means for rotating the straightening member, said straightening member comprising an external tubular shaft attached to said head stock, an internal shaft slidably mounted therein, a first bushing on said external shaft, a second bushing movable slidably relative to the internal shaft and a third bushing fixed upon the internal shaft, arms having ends pivotally connected to said first and second bushings respectively, the free ends of said arms being pivotally attached one set to another and a third arm pivotally secured to the third bushing, cross-heads pivotally attached independently to the ends of the arms remote from the bushings and to the arm adjacent the first bushing, and rollers between the cross-heads, said external shaft and said internal shaft having relative endwise movement adapted to expand and retract the positions of said rollers.

5. A straightening machine for open top cans comprising a base, a clamping support for a can, a head stock on the base above the clamping support, a straightening member on the head stock mounted above the clamping support, means for raising and lowering said head stock, said straightening member comprising an external tubular shaft attached to the head stock, an internal shaft extendible slidably therethrough, a first bushing secured to said external shaft, a second bushing movable slidably on the internal shaft on one side of the first bushing and a third bushing fixed upon the internal shaft on the side of said second bushing remote from the first bushing, arms pivotally connected to said first and second bushings respectively, the free ends of said arms being pivotally attached one set to another and a third arm pivotally secured to the third bushing, cross-heads pivotally attached independently to ends of the arms remote from the bushings, other cross-heads attached to the uppermost arms adjacent the first bushing, and rollers between the cross-heads, said external shaft and said internal shaft having relative endwise movement adapted to expand and retract the positions of said rollers, and manually operative means connected between said shafts adapted to modify the position of expansion.

6. A straightening machine for an open top can comprising a base, a clamping support for the can on the base and a head stock on the base mounted above the clamping support, a straightening member on the head stock, means for raising and lowering said head stock means for rotating the straightening member, said straightening member comprising an external tubular shaft, an internal shaft extending slidably through the external shaft, a first bushing secured to said external shaft, a second bushing slidably mounted on the internal shaft and keyed thereto, and a third bushing fixed upon the lower end of said internal shaft so that the second bushing is located between the first and third bushings, said bushings being in spaced longitudinal relation.

ship in collapsed position, sets of parallel arms pivotally connected to said first and second bushings respectively, and a set of parallel arms pivotally connected to the third bushing, free ends of said first two sets of arms being pivotally connected one set to another, cross-heads attached independently to the respective upper ends of the first two sets of arms and to the free ends of said arms on the third bushing, sets of rollers between cross-heads on opposite ends of the first set of arms and between cross-heads on the ends of the sets of arms on the second and third bushings, said internal shaft and said external shaft having relative endwise movement adapted to expand and collapse the positions of said rollers, and manually operative means connected between said external shaft and said internal shaft adapted to modify the position of expansion.

7. A straightening machine for an open top can comprising a base, a clamping support for the can and head stock on the base, a straightening head on the head stock mounted above the clamping support, and means for raising and lowering said head stock, said straightening head comprising an external tubular shaft, an internal shaft keyed to the first shaft and extending slidably therethrough and rotating means on the head connected to said first shaft, a first bushing secured to said first shaft, a second bushing slidably mounted on the internal shaft and keyed non-rotatably to said internal shaft and a third bushing fixed upon the lower end of said internal shaft so that the second bushing is located between the first and third bushings, arms pivotally connected to said first and second bushings respectively, free ends of said arms being pivotally attached one set to another and a third arm pivotally secured to the third bushing, cross-heads pivotally attached independently to the ends of the arms remote from the bushings and cross-heads attached to the arm joining the first bushing at the ends of said last arms adjacent the first bushing, and rollers between the cross-heads, said external shaft and said internal shaft having relative endwise movement adapted to expand and retract the arms and the corresponding positions of said rollers, and manually operative means comprising a crank on the head stock, a sleeve on the head stock rotatably receiving said internal shaft and connecting means between the crank and the sleeve adapted to raise and lower the sleeve whereby to modify the position of expansion of said straightening head.

8. A straightening machine for open top cans comprising a base, a clamping support for the can and a head stock on the base, a straightening member on the head stock mounted above the clamping support, means for raising and lowering said head stock and means for rotating the straightening member, said straightening member comprising an external tubular shaft attached to said head stock, an internal shaft extending slidably through the external shaft, a first bushing secured to said external shaft, a second bushing movable slidably relative on the internal shaft and a third bushing fixed upon the internal shaft, arms pivotally connected to said first and second bushings respectively, free ends of said arms being pivotally attached one set to another and a third arm pivotally secured to the third bushing, cross-heads pivotally attached independently to the ends of the arms remote from the bushings and cross-heads attached to the arms joining the first bushing at the ends of said last arms adjacent the first bushings, and

13

rollers between the cross-heads, said external shaft and said internal shaft having relative end-wise movement adapted to expand and retract the positions of said arms and the corresponding positions of said rollers, and shims on the external shaft between the second and third bushings adapted to limit the extent of expansion of the straightening member.

9. A straightening machine for an open end can having a cylindrical wall at one end and a curved wall at the other end comprising an expandable head adapted for insertion in collapsed position into the open end of the can, said head comprising a link assembly including links pivotally interconnected at adjacent ends and a pair of relatively movable shafts attached respectively to the links at ends thereof remote from said adjacent ends thereto, movement of said shafts one relative to the other being adapted to move the link assembly to a collapsed position and to potential expanded positions at the inside perimeter of said walls, and rollers comprising portions of said link assembly adapted respectively to contact the respective walls in expanded position, one of said rollers comprising a shaft and a series of cylindrical walled discs of equal diameter independently rotatable on the shaft and another of said rollers comprising a shaft and a series of discs independently rotatable on the shaft, the outer walls of said last discs having curved contours aligned each with the contour of the next adjacent disc.

10. A straightening machine for an open end can having a curved wall comprising an expandable head adapted for insertion in collapsed position into the open end of the can, said head comprising pivotally interconnected links and a pair of relatively movable shafts attached respectively to ends of the links remote from the pivotal interconnection adapted to move the links to collapsed and expanded positions, and rollers having shafts connected between ends of said links at locations remote from the relatively movable shafts, said rollers being adapted to contact the wall in expanded position, said rollers comprising a series of cylindrical walled discs of equal diameter independently rotatable on the shafts.

11. A straightening machine for an open end can having a longitudinally curved and transversely rounded wall comprising an expandable head adapted for insertion in collapsed position into the open end of the can, said head comprising pivotally interconnected links and a pair of relatively movable shafts attached respectively

14

to ends of the links remote from the pivotal interconnection adapted to move the links to collapsed and expanded positions, and rollers having shafts connected between ends of said links at locations remote from the relatively movable shafts, said rollers being adapted to assume a pressure contact with the wall in expanded position, said rollers comprising a shaft and a series of discs independently rotatable on the shaft, the outer walls of said last discs having longitudinally curved contours aligned each with the contour of the next adjacent disc.

12. A straightening machine for an open end can having a cylindrical lower wall and a curved upper wall comprising an expandable head adapted for insertion in collapsed position into the open end of the can, said head comprising pivotally interconnected links and a pair of relatively movable shafts attached respectively to ends of the links remote from the pivotal interconnection adapted to move the links to collapsed and expanded positions, and rollers having shafts interconnected between ends of said links at locations remote from the relatively movable shafts, said rollers being adapted to assume a pressure contact respectively with the lower and upper walls when in expanded position, the lower of said rollers comprising a series of cylindrical walled discs of equal diameter independently rotatable on the respective shaft and at least one intermediate disc of lesser diameter, the upper of said rollers comprising a series of discs independently rotatable on the respective shaft, the outer walls of said last discs having longitudinally curved contours aligned each with the contour of the next adjacent disc, the contour of the lowermost disc being in alignment with the next adjacent disc of the nearest lower roller.
